AIR COMPRESSOR AND THE LIKE

Albert H. Coleman, Orlando, Fla., assignor of
one-half to James M. Campbell, Orlando, Fla.

Application March 9, 1938, Serial No. 194,894

4 Claims. (Cl. 230—176)

One of the objects of my invention is to provide a type of construction that shall produce a flow of compressed air of such substantially uniform pressure that a storage tank shall not be needed.

Another object is to arrange the cylinders in such a way as to promote effective cooling of the cylinders and air passages.

Another object is to produce an efficient, compact type of construction that lends itself to the manufacture of small portable air compressors and vacuum pumps.

A further object is to provide efficient lubrication that shall require no attention over long periods of time.

In the accompanying drawings which illustrate one embodiment of my invention:

Fig. 1 is a side elevational view of an air compressor constructed according to my invention, 20 Fig. 2 is a sectional view taken substantially on line 2—2 of Fig. 3,

Fig. 3 is a sectional view taken substantially on line 3—3 of Fig. 2; and

Fig. 4 is a transverse sectional view through 25 the head of one of the cylinders.

Referring to the drawings, 10 indicates a pair of spaced frame supports for a fixed shaft 11 on which the device is rotatably mounted.

The cylinders and operating parts are carried 30 by a casing formed in two main parts generally indicated at 12 and 13. Part 12 comprises a cylindrical portion 14, one end of which is closed, except for an opening 15 for the passage of the shaft structure later described. An annular plate 35 16 forms a closure for the open end of portion 14 providing a chamber 17. Plate 16 is secured in place by machine screws 18.

Extending radially outwardly from the end of portion 14 adjacent the closure plate 16 are a plurality of box-like projecting portions 19, open at one side, which form the supports for the compressor cylinders 20. The cylinders are all in the same plane. Part 13 of the casing comprises a plate portion 21 formed to close the open sides of portions 19 and provided with a cylindrical portion 22, the outer end of which is closed by an annular plate 23 to form a chamber 24.

Chamber 17 serves as the air intake chamber and is connected to the heads of the several cylinders 20, by pipes 25. As shown in Fig. 4 the connection of pipes 25 to the interior of the cylinders is made through ball check valves 26. Chamber 24 serves as the outlet chamber and is connected to the several cylinders by pipes 27 55 through ball check valves 28.

Air is supplied to chamber 17 and permitted egress from chamber 24 through tubular bearings, generally indicated at 30, secured to the casing and by which the latter is rotatably mounted on shaft 11. Bearings 30 are identical 5 in construction, the parts being designated by the same reference characters so that a description of the inlet bearing serves to describe both.

The bearings 30 each comprise concentric spaced tubular members 31 and 32 held in spaced 10 relation by spacing collars 33 positioned at the ends of the tubular members, and rotatably mounted on shaft 11 on bearing bushings 34. Tubular member 31 is provided with a plurality of openings 35, communicating with the annular 15 space 35a between members 31 and 32, positioned outwardly of the casing, and with a plurality of openings 36 leading from said space to the adjacent chamber of the casing. Air is supplied to chamber 17 through a pipe 37 connected to a 20 stationary collar 38 provided on its inner surface with a groove 39 into which pipe 37 opens. Groove 39 communicates with openings 35 leading to chamber 17.

Egress from compression chamber 24 is provided through a pipe 40 connected to the stationary collar 38 at the opposite end of the shaft.

The collars 38 are held against the ends of the rotatable casing 12—13 by spring washers 41 and nuts 42, and are held against rotation by the 30 pipes 37 and 40.

Each cylinder 20 is provided with a piston 45 connected by links 46 to the outer end of operating lever arms 47. The arms 47 are pivoted, intermediate their ends as at 48, to bosses 49 35 formed on the inner faces of casing portions 19, and the inner ends of the levers are provided with cam rolls 50 riding in the grooves 51 of a cam 52 eccentrically fixed on shaft 11. As shown, cam 52 is built up of a plurality of plates held 40 together by screws 53 and secured to shaft 11 by a set screw 54, but any suitable cam construction may be used.

The casing and the parts carried thereby are adapted to be rotated in the direction of the arrows in Figs. 1 and 2 by a pulley 55, secured to the casing portion 14 by screws 56, and driven by a belt 57 from a motor not shown.

As best shown in Figs. 1 and 2, the cylinders 20 are secured to the casing at their bases by 50 bolts 58, at an angle of substantially 90° to the radius of the casing, that is, tangentially to their path of rotary movement, and are exposed to the air on all sides. The heads of the cylinders are curved to direct the air with substantial uni- 55

formity around all sides of the cylinders and the heads and sides are provided with cooling fins 60.

By this arrangement a very efficient cooling of the cylinders is obtained.

5 Referring to Figs. 2 and 3, it will be seen that the space between the two casing-sections 12 and 13 (note the space between the walls 19 and 21 in Fig. 3) forms a closed chamber 61 that communicates with the inner or open ends of the cylinders and contains the cam 52 and all the moving parts, i. e., the rolls 50, the levers 47, the links 46 and the pistons 45. This sealed chamber contains a suitable quantity of oil which in the operation of the machine is thrown into contact with all the moving parts and keeps them 10 properly lubricated. By reason of the tangential arrangement of the cylinders, the tendency of centrifugal force to force the oil past the pistons into the head ends of the cylinders is counter- 15 acted.

20 In operation, as the casing is rotated the cam rolls 50 travel in the grooves 51 of the stationary eccentric cam, imparting a rocking motion to the arms 47 which in turn reciprocate the pistons in the cylinders, the position of the pistons at various points in the rotation of the casing being shown in Fig. 2. As the pistons are drawn rearwardly in the cylinders air is drawn in through the pipe 37, annular groove 39, ports 35, annular 25 space 35^a, ports 36, chamber 17, pipes 25 and check valves 26 into the cylinders; and on the outward movement the air is forced out through check valves 28, pipes 27, chamber 24, ports 36, annular space 35^a, ports 35, annular groove 39 to 30 the discharge pipe 40.

35 As will be understood from Fig. 2, the inner wall of the cam grooves 51, acting on the rolls 50, force the pistons inwardly, the outer walls of said grooves producing the compression stroke.

40 The construction herein disclosed makes possible the provision of small portable air compressors adapted for use in garages, dentists' offices and many other situations where a small portable compressor is needed. The smallness and portability of the machine are enhanced by reason of 45 the fact that no storage tank is required, as the chamber 24 serves to damp the pulsations due to the successive discharges from the cylinders and thus substantially equalize the pressure of the 50 air flowing from the pipe 40.

55 The substantially uniform pressure of the air discharged from the pipe 40 is due in part to the use of five cylinders, the largest number that can be provided without interference of the levers 47 with one another in the operation of the machine.

60 The compactness and hence portability of the machine are further promoted by the use of a cam to actuate the pistons of a set of cylinders, the cylinders being all in the same plane. A series of cranks arranged along a shaft would require more room, and would necessitate the distribution of the cylinders into a plurality of planes.

65 The relatively large chamber 17 in constant communication with the atmosphere permits air to flow freely to the cylinders on the successive intake strokes of the pistons.

70 The use of a single intake pipe, as 37, permits of the use of a single air filter (not shown) for all of the cylinders.

I claim:

1. A rotary compressor or the like which comprises a stationary shaft, a casing rotatably mounted thereon, said casing being formed with generally radial projections, compression cyl-

inders mounted on said projections with the longitudinal axes of the cylinders positioned substantially tangential to the path of movement of the cylinders about the shaft, pistons in the cylinders, a stationary circular cam eccentrically mounted on the shaft inside of the casing, a lever for each cylinder pivoted in the casing, rolls on one end of said levers engaging said cam to impart a rocking motion to the levers as the casing is rotated, and links connecting the opposite ends of said levers to the pistons in the respective cylinders, inlet and outlet chambers formed in the casing, pipes connecting the chambers with the cylinders, oppositely acting check valves respectively positioned in the pipes, and means extending lengthwise of the shaft for affording constant communication with said chambers during rotation of the casing, said cylinders being secured at their bases only to the said projecting portions of the casing to provide free passage 20 of air against the head and along all sides of each cylinder when the casing is rotated.

2. An air compressor or vacuum pump having, in combination, a stationary supporting shaft; a casing rotatably mounted on and wholly supported by said shaft, said casing comprising a mechanism chamber having a series of peripheral projections, each projection providing a seat; a series of cylinders, each having a base secured to one of said seats, said cylinders being arranged substantially tangentially of and upon the periphery of the casing, each cylinder having a head; air intake and air discharge means for the head of each cylinder; means for rotating the casing on the axis of the shaft in the direction 35 to revolve the cylinders head-first and thus produce a flow of cooling air against the cylinder heads and along the walls of the cylinders; a piston in each cylinder; and mechanism within the mechanism chamber for converting the rotation of the casing into reciprocatory movement of the pistons, said chamber being adapted to contain a quantity of oil for lubricating said mechanism and pistons, the tangential arrangement of the cylinders preventing centrifugal 40 force from driving the oil into the heads of the cylinders.

3. An air compressor or vacuum pump having, in combination, a stationary supporting shaft; a casing rotatably mounted on said shaft, said casing comprising an air inlet chamber, a mechanism chamber and an air discharge chamber arranged side by side in the order stated; a plurality of cylinders arranged in a single plane and secured to the outside of said casing in the plane 55 of the mechanism chamber, each cylinder having an open end communicating with said mechanism chamber; a piston in each cylinder; means for rotating the casing; means within the mechanism chamber for converting the rotation of the casing into reciprocatory movement of the pistons; means including check valves connecting the opposite ends of the cylinders to the air inlet chamber; means including check valves connecting the last-mentioned ends of the cylinders to 60 the air discharge chamber; means for admitting air to the inlet chamber adjacent to the axis of the shaft; and means for discharging air from the discharge chamber adjacent to the axis of the shaft.

4. A rotary compressor or the like which comprises a stationary shaft, a casing rotatably mounted thereon, said casing being formed with generally radial projections, compression cylinders mounted on said projections with the longi-

tudinal axes of the cylinders positioned substantially tangential to the path of movement of the cylinders about the shaft, pistons in the cylinders, a stationary circular cam eccentrically 5 mounted on the shaft inside of the casing, a lever for each cylinder pivoted in the casing, rolls on one end of said levers engaging said cam to impart a rocking motion to the levers as the casing is rotated, and links connecting the opposite ends 10 of said levers to the pistons in the respective cylinders, inlet and outlet chambers formed in

the casing, pipes connecting the chambers with the cylinders, oppositely acting check valves respectively positioned in the pipes, and means extending lengthwise of the shaft for affording constant communication with said chambers during rotation of the casing, said cylinders being secured at their bases to the said projecting portions of the casing to provide free passage of air against the head and along the sides of each cylinder when the casing is rotated. 5

ALBERT H. COLEMAN.
